OIL-BURNING SYSTEM.

Application filed May 3, 1923. Serial No. 636,449.

This invention relates to oil burning systems and its object is to provide a safe, economical and efficient system especially adaptable to heating apparatus.

In order that the principles of the invention may be readily understood we have, in the accompanying drawings, shown certain illustrative embodiments of our invention wherein:

Fig. 1 is an elevation of a system applied to a heater, the latter being shown in section with parts broken away to save space in the drawings;

Fig. 2 is an enlarged vertical section of a portion of the fuel feed end regulating means;

Fig. 3 is a detail view partly in section and partly in elevation of one form of burner adapted for use in the present system;

Fig. 4 is a transverse section taken on the line 4—4 of Fig. 3 showing the relation of the fuel, water and air supplying means to each other and to the mixing chamber;

Fig. 5 is an elevation, partly in section, of another form of burner; and

Fig. 6 is a plan section taken on the line 6—6 of Fig. 5 illustrating the relation of the water, fuel and air supplying instrumentalities to each other.

In the drawings a fuel reservoir 1 of appropriate size and design is placed in an elevated position and connected with a burner 2 herein disposed within the fire box of a heater 3, said burner resting upon the grate 4 of said heater. The burner 2 which is of a peculiar design especially adapted for heating purposes is capable of being installed in heaters intended primarily to use various grades of coal and wood as fuel as well as in heaters designed especially for the burners of this invention. For convenience the invention has been illustrated in connection with the former type and with a heater wherein more or less of a space is formed between said burner and the walls of the heater. To fill in the space thus formed so as to confine the in-feeding air to the burner rather than allow it to escape around the exterior of the burner, said space is filled with asbestos or similar material 5.

There are numerous methods of conducting the fuel from the reservoir 1 to the burner 2 but in the present example we

preferably provide a system including a siphon 6 herein composed of two upright pipes 7 and 8 connected near the tops thereof with each other by means of a header 9, said header being inclined upwardly 60 away from the reservoir toward the upper end of the pipe 8 for reasons hereinafter described. The pipe 7 is herein shown in communication with the bottom of the reservoir 1 through a union 10 and valve 11 65 while below the valve 11 is a cap 12 which may be removed when it is desired to drain or clean the reservoir.

Included in the upright pipe section 8 is a valve casing 13 herein containing a piston valve 14 adapted to operate to stop the flow of fuel through said pipe 8 when certain conditions occur. For example in systems of the kind described there is danger of fuel feeding too rapidly to be taken 70 care of by the burner—thus causing a flooding of the heater which, if permitted to continue, would spread the flame and cause considerable damage. Therefore said valve is preferably arranged to operate to 75 shut off the flow of fuel when an excess of fuel has accumulated in the burner. Another dangerous condition likely to develop is that brought about by reason of an abnormally small flow of fuel through said 80 siphon. For example when the fuel is being fired a considerable flow will be necessary to maintain the supply necessary to feed the fire and should this supply temporarily fail the fire will be extinguished 85 and if the supply valve is not closed before the flow again starts the heater will be flooded and considerable fuel wasted with great danger of fire resulting. In fact it is a common occurrence for the entire contents of reservoirs of known systems to be completely exhausted before the extinguishing of the flame is detected.

The valve 14 has been constructed to accomplish the shutting off or the regulation 100 of the flow of fuel through said siphon when aforesaid conditions occur and by reason of its peculiar construction said valve may continue to move either up or down even after the flow of fuel through said pipe 8 has 105 been cut off or said valve 14 has seated. In other words said valve is provided with two seats 15 and 16 both of annular cylindrical form adapted to receive the piston valve 14 and by engagement with the cylindrical sur- 110

face 17 thereof shut off the flow of fuel. The annular seats 15 and 16 are mounted or arranged within an appropriate casing 19 of suitable form. Furthermore said rings 15 and 16 are separated one from the other by spaced members 18 positioned to guide the piston 14 during its movements from one seat ring to the other, the spaces between said guiding members constituting 10 bypasses 22 through which the fuel passes from one side of the piston 14 to the other when said piston is in an intermediate position between the rings 15 and 16.

It clearly is within the province of the invention to make the cylindrical portion 17 of the piston 14 fit reasonably tight within either seat 15 or 16 so as to prevent any flow of fuel therethrough when said piston aligns with one or the other of said seats but obviously pistons of this type will wear, or it is within the scope of the invention deliberately to provide a slight leakage between the said piston and one or both of said seats 15 and 16, and in either case 20 means must be provided to completely shut off the supply of fuel when certain additional movements of the piston have taken place. Therefore said piston 14 has been provided with faces 23 and 24 arranged to 25 cooperate with auxiliary seats 25 and 26 respectively at opposite ends of the casing 13 and preferably when either one of said faces is in engagement with its seat the passage of fuel through the siphon will be entirely cut off.

It will thus be seen that an extended movement of the piston valve 14 may take place in one direction or the other without completely shutting off the supply of fuel yet said supply may be increased or diminished or absolutely cut off whenever conditions require.

Means have been provided for automatically operating said piston to regulate the feeding of the fuel and herein this means preferably includes a fluid chamber 27 connected with the pipe 8 preferably below the casing 13 and approximately at the level at which it is desirable normally to maintain the fuel within the burner 2 at the starting of the operations, said level being indicated in Fig. 1 by the line $a-a$. Within the fluid chamber 27 is a float 28 connected by a rod 29 with said valve 14 whereupon any variation in the level of the fuel from that indicated at $a-a$ will effect the rising and falling of said valve 14 according to whether or not the variation of said level a is up or down from the intermediate position shown in Fig. 2. The float chamber 27 has communication through a suitable pipe line 30 with a burner 2. A tickler rod 31 is provided for the float 28 projecting through the cover 32 of said float chamber whereby the float may be manually

moved up or down as desired to start, stop or control the supply of fuel to said float chamber and said burner.

Means are also provided for initiating the flow of fuel through the siphon 6 by the ejection of air from said siphon, said means including a force pump 33 herein arranged at the lower end of the upright pipe 7, having a manually operable piston 34 which may be reciprocated in its cylinder to force fuel from the reservoir 1 to the highest point in said siphon, which highest point is herein at the top of the chamber 8 whereupon the continuity of fuel in said siphon may be established.

Under ordinary conditions as has been stated the fuel will be maintained at the level $a-a$ and when at this level the valve 14 will remain in a position with relation to the seats 15 and 16 which will permit sufficient fuel to pass through the casing 13 to supply the amount of fuel desired to maintain the burner 2 in operation, but should the flame be extinguished it is obvious that the fuel will continue to flow until said piston valve has moved by the rising of the level in the float chamber sufficiently to cut off the supply of such fuel through said valve. It will be apparent, however, that there are times when it will be desirable to break the continuity of fuel in the siphon and thus absolutely stop the supply of fuel to the burner. This condition is likely to be desired when the valve 14 becomes worn to such an extent that too great a supply of fuel will leak through the piston portion 17 and the seat 15. To accomplish the breaking of the continuity of fuel at such a time means have been provided herein consisting of an air valve 35 which is spring-pressed or self-closed against its seat 36 located preferably at the highest point in the siphon 6 herein at the upper end of the pipe 8 adjacent the elevated end of the header 9.

Cooperating with the valve 35 is a rod 37 connected with the piston valve 14. The rod 37 is not normally in engagement with the valve 35, a space 38 being provided between the end of said rod and said valve to allow a limited upward movement of said rod and the valve 14 without effecting the position of said valve 35. Thus, under normal conditions, the valve 14 will adequately control the flow of fuel under the impulse given it by the rising and falling of the fuel in the float chamber 27. Furthermore the gap or space 38 is slightly less than that space between the flat surface 23 and the seat 25 so that said valve 35 will be raised by the rod 37 immediately preceding the seating of said piston valve 14 against said seat 25.

By reason of said air valve and the means automatically to regulate and cut off the supply of fuel, the extinguishment of the

flame in the heater will result in the cutting off of the supply of fuel thereto so that no danger of flooding the heater or the room in which said heater is placed will exist. Under ordinary conditions a siphon such as that shown in the accompanying drawings would upon opening of the air valve 35 be completely drained of its contents—at least would this be true regarding the length of 10 pipe line from the level of the fuel in the float chamber 27 upwardly to said air valve 35 and from said air valve along the inclined pipe or header 9 and down the pipe 7 to a level equal to the level of the fuel with 15 in the fuel receptacle 1 but if this is allowed to happen in the present system the force pump 33 will again have to be called into action to start the flow of fuel through the siphon. It is desirable after the dangerous 20 conditions have been removed and the excess fuel drained or evaporated from the burner that the feeding of fuel be automatically renewed and for this purpose the header 9 has been upwardly inclined as hereinbefore described. In the pipe 7 a check valve 35' is provided which retains the section of the pipe 7 above said check valve and all of the header 9 filled with fuel even though said valve 35 has been 25 opened. With the fuel in said pipe 9 on the verge of overflowing into the pipe 8 upon the closing of the valve 35 by the lowering of the float an air pocket obviously will be produced between the level of the fuel in 30 said float chamber and the level of fuel at the upper end of said header 9 and this air pocket, although slightly elastic, will be sufficient, upon the dropping of the level in 35 said float chamber to start the flow of fuel over the verge of said header 9 thus renewing 40 the siphon or continuity of liquid in said siphon. Should the level of the fuel within the burner or float chamber for any reason drop below the safety point or to a 45 point where the flame will be extinguished, the valve 14 will be automatically operated by said float to shut off the supply of fuel, thus preventing the discharge of the entire 50 contents of the reservoir.

Within the scope and purpose of the invention various types of burners may be employed but in Figs. 3 and 4 we have illustrated a preferred form of burner which embodies in its construction a fuel receptacle 40 herein of annular formation having an inner wall 41 and an outer wall 42, said inner wall being slightly lower than the outer wall to confine the flow of fuel upon the flooding of said receptacle toward its center where is located the mixing chamber of the burner. For convenience in cleaning, said receptacle has a removable lining 43, the inner and outer walls whereof coincide in respect to height with the walls 41 and 42 of said receptacle.

Adjacent to said fuel receptacle is a water chamber 44 which, for convenience, encircles the fuel receptacle and is formed in part by the outer wall 42 of said fuel receptacle and in part by an outer annular wall 45 extending slightly above said wall 42. The water and fuel containers, for convenience, are arranged in an annular casting provided with a plurality of lugs or feet 47 arranged to rest upon a cylindrical support extending 75 upwardly from the base 49 of the burner.

Provided between the upper end of said cylindrical support 48 and the inner wall 41 of said fuel receptacle is an annular space 50 forming a passage through which excess fuel from said fuel receptacle is allowed to escape so as not to flood the burner. Below said annular space 50 the base 49 of said burner is formed into a trough 51 wherein is a suitable substance constituting a wick 52 85 adapted to absorb the fuel which descends from said fuel receptacle and facilitate the combustion of said fuel, or if desired, said trough may be supplied with fuel and the latter ignited to initiate the operation of the 90 burner.

Surmounting the casting 46 is a plate or cap 53 herein adapted to rest tightly upon said casting along the outer rim 54 thereof. Said cap is also supported upon the upper edge of the inner wall 41 of said fuel receptacle herein at spaced points by lugs 55 which are so arranged as to provide an outlet 56 for the vapor produced in the fuel receptacle 40. The cap 53 has a central 100 opening 57 aligning and herein substantially coextensive with the center of the interior of the cylindrical support 48 which members together form a mixing chamber 58. The lower end of the cylindrical support 48 is 105 open to the space below the grate 4 and constitutes an air duct through which air is supplied to the mixing chamber to provide the proper mixture for the fuel. The upper surface of the cap 53 is preferably provided 110 with radial ribs 59 which form suitable channels leading to the ignition region or flame edge of the burner and these ribs also provide increased heating surfaces for increasing the temperature of the charge in its 115 passage to said flame edge, thus greatly increasing the efficiency of combustion.

For convenience the ribs 59 are reduced in height at 60 and constitute supports for a deflecting plate 61 which surmounts said cap 53 and directs the air and vapor after being mixed outwardly to the flame edge of the burner which latter is formed by the outer rim 62 of said deflecting plate and the corresponding edge of the casting 46. The deflecting plate 61 is preferably designed to produce the deflection of said vapor and air without retarding the flow thereof. The cap 53 and the deflector 61 preferably merely rest one upon the other and upon the annu-

4
lar casting 46 and may quickly and easily be removed for cleaning.

By reason of the arrangement of the cylindrical support 48 and its trough-like base

- 5 51 the infeeding air will be directed to the mixing chamber and the mouth of the fuel receptacle without contacting with and chilling said receptacle and because of the proximity of said fuel receptacle and water chamber to the flame edge of said burner, said fuel may be maintained at a high temperature and thereby greatly enhance the vaporization both of the water and of the fuel. The vapor arising from the water in
- 10 15 said water chamber will be directed by the under surface of said cap 53 over the wall 42 and across the top of the fuel receptacle mixing with the fuel vapor at this point and passing therewith through the slots 56 to the mixing chamber where mixture is effected with the infeeding air whence they will be directed by the cap plate 61 through the reduced segmental slots 63 to the flame edge of said burner and ignited.
- 20 25 25 The fuel supply pipe 30 from the siphon tube 6 enters the bottom of said fuel receptacle and extends slightly above the bottom surface thereof as shown at 64 thus preventing the sediment from flowing back into the pipe 30 and clogging the same.
- 30 35 35 the pipe 30 and clogging the same.

Any appropriate means may be provided for supplying water to said burner and in the present example I have provided a water receptacle 65 connected by a pipe line 66 through the bottom wall of the member 47 with the water chamber 44, a valve 67 being inserted in said pipe line to regulate or shut off the supply of water to said water chamber.

- 40 45 Obviously the valve 67 may be set so as to supply the amount of water necessary for ordinary use but it is inevitable that the demand upon this will vary as does that for fuel, therefore, it is desirable to provide means automatically to control the supply of water, which, in the present example, includes a valve 86 in the pipe line 66, said valve being preferably similar to the valve 14 hereinbefore described.

- 50 55 50 For convenience the valve 86 is enclosed in a suitable case 87 and is operatively connected like 14 with a float 89 enclosed within a suitable float chamber 88, said valve 86 being operated to close either upon the presence of an excess of water or too little thereof in the float chamber 88 and these conditions obviously may be effected by the position of the valve 67.

It is obvious that after the burner has once been started, heat produced by combustion will maintain the various walls and surfaces of the device at sufficiently high temperature to produce the most satisfactory mixture for an efficient combustion of the fuel and air due to the proximity of

the fuel receptacles and to the arrangement for providing air to the combustion chamber but in order to effect ignition and also the heating of the fuel and air to insure proper vaporization for starting the device 70 into operation, extraneous means may be provided. For this purpose, if desired, the trough 51 may be filled with fuel and ignited and heat thereof will cause the walls of the cylindrical support 48 to become 75 properly heated so as to increase the temperature of the air entering the air passage in the cylindrical support 48 to the most desirable temperature for mixing and also the flames from said burning fuel will 80 contact with the under surface of the annular casing 46, thus providing heat necessary to effect the initial vaporization of the fuel within the fuel receptacle 40 and the water in the chamber 44.

It is also within the scope of the invention to provide a pilot light 67' which may, if desired, be kept burning low at all times so that in case of the extinguishment of the flame by reason of a reduction in the supply of fuel to the burner or otherwise said pilot will upon the replenishing of the fuel automatically ignite and continue the operations of the burner.

From the foregoing it will be apparent that the fuel, air and vapor are all heated prior to mixing and the infeeding air is prevented from contacting directly with the fuel receptacle, thus preventing chilling of the fuel therein.

In the form of burner shown in Figs. 3 and 4 the air is fed into the burner upwardly to the mixing chamber and centrally of the burner but it is within the scope and purpose of the invention to vary quite materially the relations of the air-supplying means and fuel receptacles and in Figs. 5 and 6 we have illustrated a modified form of burner wherein the air is admitted at the sides and brought down into the mixing chamber while the fuel is admitted centrally thereof.

In this example a fuel receptacle 68 is arranged centrally of the burner and fuel is supplied thereto through a fuel pipe 69 arranged centrally of said receptacle and protruding upwardly a substantial distance above the bottom to prevent sediment from flowing back and clogging said pipe. For convenience the fuel receptacle 68 is made frustoconical in shape with its upper tapering walls 70 provided with a series of diverging ribs 71 which greatly increase the heat radiating surface of said receptacle.

Surmounting said receptacle 68 is a cupola-like structure 72 closed at its upper end and provided with a plurality of orifices 73 through which, when the burner is flooded, the fuel is discharged upon the upper ribbed surface of said receptacle and

vaporized. The orifices 73 are arranged slightly above the level represented by the dotted line b , b to which level the fuel is allowed to rise and be maintained by the 5 hereinbefore described float 28 and valve 14 cooperating therewith only when the burner is not in operation, because during the operation with conditions normal the heat of the burner will vaporize the fuel the moment 10 it enters said receptacle no surplus being allowed to collect because of the cooperative regulation of the valve 14 and hand operated valve 90 arranged in said pipe line.

The receptacle 68 is arranged within a 15 base member 74 provided with an upwardly flaring air deflecting bottom 75.

Surmounting said base 74 are air tubes 76 herein three in number which align with openings 77 in the base member 74. The 20 air tubes 76 are preferably united by a circular plate 78 arranged at the upper end of said air tubes and herein formed integral with said plate is a depending curtain-like member 79 preferably cylindrical and terminating a slight distance above the top ribbed wall 70 of said fuel receptacle to provide a discharge orifice 80 for the mixture. The upper ends of the air tubes 76 and said plate 78 are surmounted by a deflecting cap 30 plate 81 preferably resting against the periphery of said plate 78 and being so constructed that the air admitted through the grate 4 of the heater and through said air tubes will be deflected toward the center 35 of the burner past the orifices 73 of the fuel receptacle, thence downwardly against the ribbed upper wall of said fuel receptacle to said discharge orifice 80, herein the region of combustion. The curtain member 70 enclosing 40 the cupola 72 of the fuel receptacle forms a mixing chamber 82 where the air supplied through the air tubes 76 and the fuel discharged through said orifices are mixed properly to form the charge which 45 is ignited preferably as it is discharged at 80 and produces a flame which extends from said orifice 80 to the outer edges 83 of the cap plate 81 which, in the present example, is the flame edge of said burner.

50 In order to supply water vapor to the burner to increase the efficiency of the charge a coil of pipe 84 is preferably arranged within said burner resting upon the plate 78 one end of said coil having communication at 85 with the top of the cupola 72, the other end of said coil being connected with a supply tube 86 herein entering said burner through one of said air tubes 76. With this burner as with the one shown in Figs. 3 and 55 4 the air conducting tubes will be heated by the flame from the burner so that the air entering the mixing chamber will be pre-heated; likewise the upper surface of the fuel receptacle; also the water supply tube 60 will be heated so that both the water and

the fuel will be vaporized before they reach said mixing chamber and furthermore by reason of the protecting wall 75 of the base 74 the cold air entering the tubes 76 will be prevented from contacting directly with the 70 fuel receptacle and thus eliminate all danger of chilling the fuel before mixture. A feature of this burner as of the one shown in Figs. 3 and 4, is that all parts are readily removable for the purpose of cleaning. 75

Having thus described the best modes known to us for producing our invention and certain specific embodiments of means whereby, if desired, such may be carried out we desire it to be understood that we have 80 employed terms in a generic sense and not for purposes of limitation, the scope of the invention being set forth in the following claims:

1. In an oil burning system, a burner, a 85 fuel reservoir, a siphon to conduct fuel from said reservoir to said burner, said siphon having a portion of pipe elevated above said reservoir, a float, a valve arranged in said siphon actuated by said float, an air valve 90 arranged in said elevated pipe and means extending from said valve to said air valve to operate the latter upon excessive upward movement of said float and break the continuity of liquid in said siphon. 95

2. In an oil burning system, a burner, a fuel reservoir, a siphon to conduct fuel from said reservoir to said burner, said siphon including two upright members and an inclined header arranged above said reservoir 100 and providing communication between the upper portions of said upright members, an air valve arranged near the upper end of said header, and float actuated means to open said air valve and admit air into said 105 siphon.

3. In an oil burning system, a burner, a fuel reservoir, a siphon to conduct fuel from said reservoir to said burner, a piston valve to control the flow of fuel through said 110 siphon, a float chamber, a float in said chamber connected with said piston valve and adapted to effect the closing of said valve either upon an abnormal rise or fall of fuel in said float chamber and 115 an air valve for said siphon arranged to be operated by movement of said piston valve beyond its closing position.

4. In an oil burning system, a burner, a fuel reservoir, a siphon to conduct fuel from said reservoir to said burner, a piston valve arranged in said siphon, a float chamber, a float in said chamber connected with said 120 piston valve adapted to operate said valve upon the rise or fall of fuel in said float chamber to regulate the flow of fuel through said siphon and an air valve for said siphon adapted to be opened upon the rising of said float to an abnormal height thereby to 125 destroy the continuity of fuel in said siphon. 130

5. In a liquid controlling device a liquid reservoir, siphonic means including a pipe elevated above said reservoir to conduct liquid from said reservoir, a fluid chamber connected with said siphon, a valve to control the discharge of liquid from said siphon into said fluid chamber, a float actuated by abnormal changes in the level of liquid in said fluid chamber to close said valve, and automatic air supplying means in said elevated pipe operated by excess movement of said float to stop the flow of liquid through said siphon upon an abnormal change in the level of liquid in said fluid chamber.
- 10 6. In combination, a fuel consuming device, a fuel reservoir, an auxiliary fuel container interposed between said reservoir and said container, siphon means to convey fuel from said reservoir to said container, valve means responsive to a predetermined rise 20 or fall of the fuel in said container to cut off the supply of fuel thereto, means to convey fuel from said auxiliary container to said fuel consuming device and means effected by an abnormal operation of said 25 valve means to break said siphon.

In testimony whereof, we have signed our name to this specification.

ANGELO MINELLA.
ELVIN D. MACARTHUR.
